UNITED STATES PATENT OFFICE.

CHARLES H. PIERCE, OF PHILADELPHIA, PENNSYLVANIA, ASSIGNOR TO
ELMER H. GREY, OF SAME PLACE.

CUE-TIP.

SPECIFICATION forming part of Letters Patent No. 243,299, dated June 21, 1881.

Application filed May 1, 1880. (No model.)

To all whom it may concern:

Be it known that I, CHARLES H. PIERCE, a citizen of the United States, residing in the city and county of Philadelphia, and State of Pennsylvania, have invented a new and useful Improvement in Billiard-Cue Tips, which improvement is fully set forth in the following specification and accompanying drawings, in which—

10 Figure 1 is a side elevation of the tip embodying my invention. Fig. 2 is a face view thereof. Fig. 3 represents a sectional view of my improved cue-tip.

Similar letters of reference indicate corresponding parts in the figures.

The object of my invention is to avoid the use of chalk for cue-tips, which article, as is well known, is a matter of expense, soils the cloth of the game-table, the floor of the apartment, and the clothes of the player, interrupts and delays the game, owing to the time necessary to reach the chalk and apply it to the cue, and distracts the attention of the player. Furthermore, in the excitement of the game 20 the player may neglect to chalk the cue, and thus fail in the shot; but chalk, even when properly and timely applied, is somewhat defective, and attempts have been made to supply its place by forming the tips of various 25 compositions, which, however, have not answered the purpose.

My invention is designed to remedy the defect aforesaid and overcome the objections stated; and it consists in forming the tips of 30 emery and soft or vulcanized rubber, the emery being vastly in excess of the rubber.

Referring to the drawings, A represents a tip, which is of usual form, and is applied to the cue in the well-known manner.

In producing the tip embodying my invention I take about five parts of emery and about one part of soft or vulcanized rubber, and mold the mass into tips of the desired form. Should the tips have a glazed surface, they may be turned to remove the same.

A tip thus constructed possesses all the advantages of a tip in use, with the addition of an increased frictional surface, better results and greater durability, and obviates the necessity of chalk and chalking, thus avoiding interruptions in the game, and saving time, labor, and expense.

I am aware that it has been proposed to form a cue-tip of rubber and chalk or some silicious substance. This I disclaim. Emery is a variety 55 of corundum, consisting mainly of alumina. It is sharp and gritty, and takes better hold of the balls, and wears longer than silicious substances; hence I have made an improvement in the art; and therefore,

Having fully described my invention and the advantages thereof, what I claim as new, and desire to secure by Letters Patent, is—

The cue-tip formed of emery and soft or vulcanized rubber, the emery being in excess, 65 substantially as and for the purpose set forth.

CHARLES H. PIERCE.
